UNITED STATES PATENT OFFICE.

HERMAN SCHUM, OF NEW YORK, N. Y.

APPARATUS FOR PLAYING BASE-BALL.

1,073,783.

Specification of Letters Patent. Patented Sept. 23, 1913.

Application filed March 15, 1912. Serial No. 683,928.

To all whom it may concern:

Be it known that I, HERMAN SCHUM, a citizen of the United States, residing in the city, county, and State of New York, have 5 invented new and useful Apparatus for Playing Base-Ball, of which the following is a description.

This invention relates to apparatus for playing base-ball and has for its object the 10 production of apparatus suitable for playing a game of base-ball, according to the usual rules thereof, that is adapted to enable the players to exercise skill and judgment in the use of the apparatus when 15 playing the game.

Referring to the drawings forming part 20 of this specification, Figure 1 is a view in perspective of apparatus for playing base-ball made in accordance with this invention; Fig. 2 is an elevation showing in detail certain parts of the apparatus; Fig. 3 is a plan view from below, and Fig. 4 is a plan view from above, of the parts shown in Fig. 2.

25 In the several figures of the drawings, like letters denote like parts.

A is a flat, oblong surface of wood or other suitable material which forms the field for the game.

30 a, b, and c are squares upon the field A which constitute, respectively, first, second and third base. A movable end d of the turn-piece Q may be the home-plate.

e and f are the foul lines.

35 B B are guards along the two sides, and B', B'' are, respectively, guards along the head and foot of the field A. Each side guard B is provided with an opening C, which extends from the foul line e or f to- 40 ward the head of the field.

D D and D' are slanting boards above the guards at the two sides and at the head of the field and represent the bleachers or seats for spectators at a game of base-ball.

45 Beneath each bleacher D, on each of the two sides of the field, is an inclined channel E affording a passage from the opening C to the pocket F. Between the pockets F F, at the foot of the field, are several 50 other pockets designated 1, 2, 3 or H R. These pockets are below the level of the field A. Across the foot of the field is a line of posts G G and a rope I carried by the posts.

55 Of the players in the field, 4 is the catcher, 5 the pitcher, 6 the first baseman,

7 the second baseman, 8 the short stop, 9 the third baseman, 10 the right fielder, 11 the center fielder and 12 the left fielder, while 13 is a man of the opposing side who 60 has reached first base. Each man is movable.

J J are two standards in the upper part of the field supporting the cross-bar K.

L is a ball, preferably of lead or like 65 heavy and inelastic material, suspended from the cross-bar K by a thread or cord M.

N is a recess and O is a back-stop at the head of the field.

P is a horizontal bar forming, preferably, 70 part of a U-shaped piece of wire supported by the back-stop, as shown in Fig. 1.

Q is a turn-piece pivoted on or turning with a pin or screw g. One end of the turn-piece Q is provided with a socket h to hold 75 the ball i made, preferably, of steel or other elastic material.

j is a bat pivotally secured to the head k of the bat-post m, as shown clearly in Fig. 2.

R is a plate, preferably made of metal, 80 forming part of the surface of the field A and level with the other parts thereof. The plate R is provided with a semi-circular slot n.

The turn-piece or movable carrier Q is 85 provided at one end with a hole through which the bat-post m passes. The head k of the bat-post is greater in diameter than the lower part of the bat-post. It is also greater in diameter than the hole in the 90 turn-piece Q through which the bat-post passes. Hence, the head k forms a shoulder which rests upon the upper surface of the turn-piece Q and sustains the bat-post m in position, as shown in Fig. 2. The bat j 95 extends horizontally from the head k of the bat-post and is of such length and of such distance above the upper surface of the turn-piece Q that it will strike the ball i resting in the socket h when the bat is 100 caused to swing around in the manner hereinafter described.

o is a movable plate on the under side of the plate R. The plate o is pivoted upon the pin or screw g upon which the turn-piece Q is pivoted and the pin or screw g holds the plate o and the turn-piece Q in their proper pivoted positions, the pin or screw g passing through a hole in the plate R in order to connect the plate o and the 105 turn-piece Q. The position of the plate o, beneath the plate R, is, preferably, such

that it will at all times close the slot *n*. The plate *o* is provided with a hole so positioned that when the plate *o* is turned about its pivot *g* the hole will move along the slot *n*. Through this hole in the plate *o* the bat-post *m* passes, so that when the turn-plate *Q* is turned on its pivot, the bat-post, which passes through a hole in the turn-piece *Q* and slot *n* and a hole in the plate *o*, will cause the plate *o* to turn with it on the same pivot *g*. The ends of the slot *n* limit the movement of the bat-post *m* and thereby limit the movement of the turn-piece *Q* and plate *o*.

15 The lower end of the bat-post *m* is provided with an arm *p* secured thereto, as by passing the arm *p* through a hole in the lower end of the bat-post *m*. The arm *p* extends horizontally from the bat-post *m*.
 20 At one side of the plate *o* a notch *o'* may be made, as shown in Fig. 3. By making a short cut in the metal of the plate *o*, a strip *q* of metal may be formed, which, when slightly bent, forms a convenient device for the attachment thereto of one end 25 of a wire or other suitable spring *r*, as shown in Figs. 2 and 3. The wire spring *r* may pass around the bat-post *m* above the horizontal arm *p* and then around the horizontal arm *p*. This arrangement and resilience of the wire spring *r* are, as shown in the drawings, such as to cause the bat *j* to swing over the socket *h*, striking the steel ball *i*, when the free end of the bat is 30 drawn toward the head of the field and the spring is permitted to act. In Fig. 4 the bat is shown in dotted lines at *j'* to indicate a position given to it, by adjustment of turn-piece *Q* and parts hereinafter described, and in full lines at *j* when in motion, swinging toward the ball *i* under action of the spring.

Beneath the plate *o* is a two-armed lever *S* having for its fulcrum a pin or screw *s* 45 that passes through a hole in a bracket *t* affixed by a screw *u* to the under side of the plate *R*. One arm of the lever *S* is provided with a notch *v*, adapted to catch and hold the horizontal arm *p* secured to the bat-post *m*, and inclines to a point to permit arm *p* to ascend the incline until it reaches the notch, depressing that end of the lever *S* as it does so. To the other end of the lever *S* a wire rod *w* is attached at 50 one of its ends, as shown in Figs. 2 and 3. A wire or other suitable spring *x*, which may be secured at one end by passing it around the screw *u* or in any other suitable manner and which presses with its other end upon the under side of the arm of the lever *S* provided with the notch *v*, tends 55 constantly to raise that arm of the lever *S*.

The arrangement and relative positions of the parts are such, as shown in the figures of the drawings, that when the free

end of the bat *j* is moved sufficiently far toward the head of the field, the horizontal arm *p*, carried by the bat-post *m*, will slide along the incline of the pointed end of the lever *S*, depressing that end of the lever *S* until it reaches the notch *v*, into which it will enter and where it will be held, the spring *x* forcing the pointed end of the lever *S* upward as soon as the arm *p* enters the notch *v*. The bat *j* will be held in the position thus given to it until an upward pull on the rod *w* lowers the pointed end of the lever *S* and frees the arm *p* from engagement with the side of the notch *v* that holds it, whereupon the pressure of the wire spring *r* will cause the bat to swing and strike the steel ball *i* in the manner above described.

T is a device for automatic umpiring. It consists, preferably, of three upright posts, 85 *t*, *t'*, *t''*. Each of the outer posts *t* and *t''* is at such a distance from the center post *t'* as to leave a sufficient space between it and the center post to permit the ball *L* of lead to pass freely through the space. 90 The three posts are pivoted upon a rod *y*, as clearly shown in Figs. 2 and 4, the rod *y* being carried by a bracket *z* secured to the upper surface of the plate *R*. The lower ends of the three posts are provided with 95 horizontal projections *a'*, *a'*, *a''*, one for each post, and these projections *a'* rest upon the upright part of the bracket *z*, maintaining the posts in a substantially upright position, inclining, however, slightly toward the 100 pitcher *S*. The two outer posts are free to turn on the rod *y* toward the backstop *O*. The rod *w*, which, as above stated, is attached to one end of the lever *S*, and which passes through a hole *w'* in the plate *R*, is 105 attached at its other end to the projection *a''* of the center post *t''*. Hence, a blow struck by the leaden ball *L* upon the center post *t''* will raise the rod *w* and the end of the lever *S* to which it is attached, thereby depressing the other end of the lever *S*, freeing the arm *p* from the notch *v* and permitting the pressure of the spring *r* to cause the bat *j* to swing and strike the steel ball *i*. For 110 convenience a wire *U* may be bent and passed around the rod *y* in the manner clearly shown in Fig. 4 and employed as a lifting-device for raising the posts *t* and *t''*, when they have been knocked over toward the back-stop *O*, by pressing on one end of 115 the wire to move its projecting horizontal ends upward and forward. The apparatus may also comprise a second device for 120 umpiring *V*, consisting of a needle and of a dial with spaces marked *S* or *O*; *S* indicating "safe" and *O* indicating "out".

Each of the nine men in the field is provided with a pocket *Y* at his feet or base, projecting forward horizontally along the surface of the field. This pocket is, prefer- 125

ably, formed, on three sides, of a thin, flat rim *W*, of metal or other suitable material, and of a somewhat curved, vertical and higher piece *X* at the rear of the pocket between the legs of the player. The surface of the field *A* may form the bottom of the pocket. The players may also be made with their arms outstretched and their bodies curved and leaning slightly forward, so that the shape of each man is adapted to intercept and stop the ball *i*, while the pocket at his base is adapted to catch and hold the ball whenever the ball enters it, the elevated portion at the rear of the pocket effectively preventing the ball from passing on between the player's legs. The pocket constructed in the manner stated also serves to give to each man a firm footing.

From the foregoing description of the apparatus for playing base-ball made in accordance with this invention, its use and mode of operation will now be readily understood. Two persons opposing each other may be supposed to play the game. Upon deciding in any suitable manner, as by the use of the umpiring device *V*, which side is to take the field and which is to go to the bat, the person taking the field arranges the nine players according to his judgment and the usual rules of a base-ball game, or, as may be agreed upon. The one going to the bat adjusts the bat and the ball *i* as herein-after described, the bat being ready to swing and hit the ball, under the action of the spring, when the arm *p* of the bat-post *m* is released from the notch *v* of lever *S*. The person taking the field, then takes hold of the suspended leaden ball *L*, draws it to a position over second base or thereabout and endeavors to so direct the forward swing or passage of the ball that it will pass through the space on either side of the center post *t''*; that is to say, through the space between the post *t''* and the post *t'* or between the post *t''* and the post *t'''*. If the ball so passes, "a strike" is called. If, however, the ball strikes the post *t'* or the post *t'''*, it will knock it over and "a ball" is called. If the ball passes on the outside of the post *t'* or of the post *t'''*, it is a "passed ball". If the ball strikes the center post *t''*, the bat *j* will be released in the manner above described and swing and strike the steel ball *i*, knocking the ball from its socket *h*, and causing it to pass upon the field.

Should the ball, when hit by the bat, be a "foul ball", it will be received in the opening *C* on either side of the field, whereupon it will roll down the inclined channel *E* and enter the corresponding pocket *F* at the foot of the field. Should the ball, when hit, be a "fair ball" and be caught in the pocket of one of the men, the striker is "out", and no man on base may advance.

Should the ball, when hit, pass the men and pass the posts *G* and the rope *I* and enter a pocket marked 1, 2, 3 or *H R*, it is a one-base or a two-base or a three-base "hit" or a "home run", according to the pocket into which the ball enters. Whenever such a "hit" is made the striker takes the proper base and any man on base is correspondingly advanced on the bases, as in the regular game of base-ball. In case of a "passed ball", a man on base is advanced one base.

Should the ball not roll "foul" but roll "fair" and not be caught in the pocket of any man and not reach any pocket at the foot of the field, being stopped, perhaps, by striking against some man in the field or against a post *G* or the rope *I*, in such case a decision is called for by the umpiring device *V*, which may be used for decisions on the bases only, and the striker will either be declared "out" or "safe", according as the point of the needle rests upon *O* or *S*; or, in such case, should there be a man on base, the play may be for him instead of for the striker and the man on base may be declared "safe" or "out" according to the decision of the umpiring device *V*, and thus a "run" or an advance on the bases may, perhaps, be prevented.

It should be understood, of course, that it is the object of the player pitching the leaden ball *L* to avoid striking the center post *t''*, since if that post be struck his opponent will probably secure an advantage unless the ball rolls "foul". The pitcher should also avoid "balls" and "passed balls" and should pitch for "strikes", as is usual in the regular game of base-ball.

If the leaden ball *L* when pitched passes the three posts *t'*, *t''* and *t'''*, the thread or cord *M* will contact with the cross-bar *P* and the momentum of the ball *L* will cause the ball to pass back over the cross-bar *P* and wind the thread or cord *M* for one or two turns about the cross-bar, the thread or cord *M* being of a length suitable and proper for playing the game in the manner indicated. Hence, the cross-bar *P* acts as a catcher.

Before the player taking the field begins to pitch with the ball *L* his opponent revolves the turn-piece *Q* on its pivot *g* so as to bring the socket *h* into the desired position. The steel ball *i* is also placed in the socket *h* and the free end of the bat *j* is moved toward the head of the field turning the bat-post *m* with it until the arm *p* enters the notch *v* of lever *S* and the parts are held in the positions thus secured. Should the center post *t''* be then struck by the ball *L*, the pull of the rod *w* upon one end of the lever *S* will free the arm *m* from the notch *v* and the bat will thereupon swing and hit the ball *i*. By rotating the turn-piece *Q* and thus changing the position of the socket *h* and of the steel ball *i*, the di-

rection to be given to the steel ball *i* when struck by the bat can be regulated and determined. Considerable skill can, therefore, be displayed in sending the steel ball *i* when struck by the bat *j* in a given direction, and in thus causing the ball to avoid the men placed in the field by the opposing player. According to the position given to the turn piece *Q* the steel ball *i*, when struck, can be made to roll "foul" or "fair" and any one understanding the game of base-ball will understand that the apparatus described can be used in carrying out innumerable points of the game of base-ball not necessary to describe here, since the points of the game are so well understood.

The apparatus forming the subject matter of this invention affords opportunity for playing a scientific game of base-ball in which skilful pitching and good fielding are special features for one side and place hitting is a special feature for the opposing side.

The back-stop *O* may be green in color and the posts *t*, *t'* and *t''* may be red, for the purpose of securing a contrast and enabling the pitcher to observe and pitch more accurately. The field *A* should, preferably, be elevated to permit the pockets at the foot of the field to be below the surface thereof, to permit the channel *E* to incline slightly and to afford space for the parts below the plate *R*.

From what has been said, it will be seen that the game of base-ball as played with the apparatus described and made in accordance with this invention is, like the regular games of base-ball played today, a game largely in the hands of the pitcher, and the game may be called "A pitcher's battle". It will also be seen that the several parts of the apparatus automatically decide the points of the game. For instance, the automatic umpiring device *T* determines, in the manner above stated, the effect of the balls pitched, the foul lines and openings *C* determine the foul balls, the pockets at the feet of the players determine the balls caught, the pockets at the foot of the field determine the hits and the number of bases obtained thereby, while decisions on the bases may be made by the use of the umpiring device *V*.

What I claim is:

1. In apparatus for playing base-ball, the combination of a movable turn-piece provided with a socket for a ball near one end, a bat movably connected with the turn-piece near its other end, and a spring for actuating the bat, substantially as described.

2. In apparatus for playing base-ball, the combination of a movable turn-piece, a bat movably connected with the turn-piece, means for actuating the bat, means for restraining the action of the actuating means,

and means for releasing the restraining means, substantially as described.

3. In apparatus for playing base-ball, the combination of a movable turn-piece, a bat movably connected with the turn-piece, a spring for actuating the bat, a lever, means for detachably connecting the spring with the lever, and means for releasing the connection between the lever and the spring, substantially as described.

4. In apparatus for playing base-ball, the combination of a movable turn-piece, a revolute bat-post carried by the turn-piece, a bat carried by the bat-post, a spring for revolving the bat-post, an arm carried by the bat-post, a lever provided with a notch for receiving and holding the arm, a spring pressing upon the lever to hold the arm within the notch and means for disengaging the arm from the notch of the lever whereby the bat is caused to swing by the action of the spring upon the bat-post, substantially as described.

5. In apparatus for playing base-ball, the combination of a movable turn-piece, a bat movably connected with the turn-piece, a spring for actuating the bat, means for restraining the action of the spring, a post, and means connected with the post for releasing the spring from the action of the means restraining its action, substantially as described.

6. In apparatus for playing base-ball, the combination of a bat, a spring for actuating the bat, a lever, a post, means for checking the action of the spring engaging with one end of the lever and means connecting the post with the other end of the lever for releasing the engagement between the lever and the checking means, substantially as described.

7. In apparatus for playing base-ball, the combination of a turn-piece, a bat, a revolute bat-post carrying the bat and connected with the turn-piece, a revolute plate connected with the bat-post, a pivot upon which the turn-piece and revolute plate are pivoted and a spring for revolving the bat-post, substantially as described.

8. In apparatus for playing base-ball, the combination of a turn-piece, a bat, a revolute bat-post carrying the bat and connected with the turn-piece, a revolute plate connected with the bat-post and a spring secured at one end to the revolute plate for revolving the bat-post, substantially as described.

9. In apparatus for playing base-ball, the combination of a turn-piece, a bat, a revolute bat-post carrying the bat and connected with the turn-piece, a plate provided with a slot through which the bat-post passes, a revolute plate connected with the bat-post and a spring for revolving the bat-post, substantially as described.

10. In apparatus for playing base-ball, the combination of a turn-piece, a bat, a revoluble bat-post carrying the bat and connected with the turn-piece, a plate provided with a slot through which the bat-post passes, a revoluble plate connected with the bat-post and a spring secured at one end to the revoluble plate for revolving the bat-post, substantially as described. 5
- 10 11. In apparatus for playing base-ball, the combination of a turn-piece, a bat, a revoluble bat-post carrying the bat and connected with the turn-piece, a plate provided with a slot through which the bat-post passes, a 15 revoluble plate connected with the bat-post, a spring for revolving the bat-post, an arm carried by the bat-post, a lever adapted to contact with the arm, a spring pressing upon the lever, a post and means connecting the lever with the post to free the arm from contact with the lever, substantially as described. 20
12. In apparatus for playing base-ball, the combination of a plate provided with a slot, a turn-piece and a bat above the plate, a revoluble bat-post carrying the bat and connected with the turn-piece and passing through the slot in the plate, a revoluble plate connected with the bat-post, a spring secured at one end to the revoluble plate for revolving the bat-post, an arm carried by the bat-post, a lever adapted to contact with the arm, a spring pressing upon the lever, a post and means connecting the lever with the post to free the arm from contact with the lever, substantially as described. 30
13. In apparatus for playing base-ball, the combination of a field provided with a plate in the surface thereof, said plate being provided with a slot, a turn-piece and a bat above the plate, a revoluble bat-post carrying the bat and connected with the turn-piece and passing through the slot in the plate, a revoluble plate connected with the bat-post, a spring secured at one end to the revoluble plate for revolving the bat-post, an arm carried by the bat-post, a lever adapted to contact with the arm, a spring pressing upon the lever, a post and means connecting the lever with the post to free the arm from contact with the lever, substantially as described. 40
14. In apparatus for playing base-ball, the combination of a movable turn-piece, a bat movably connected with the turn-piece, a spring adapted to actuate the bat, means adapted to restrain the action of the spring, a thread, a ball suspended by the thread, a 50
- post, and means connected with the post for freeing the spring from the action of the means restraining it when the post is struck by the ball, substantially as described. 60
15. In apparatus for playing base-ball, the combination of a thread, a ball suspended by the thread, a bat, a spring for actuating the bat, means for restraining the action of the spring, a post, and means connected with the post for freeing the spring from the action of the means restraining it when the post is struck by the ball, substantially as described. 65
16. In apparatus for playing base-ball, the combination of a thread, a ball suspended by the thread, a bat, means for actuating the bat, means for checking the action of the actuating means, three posts with spaces therebetween and means connecting one of the posts with said checking means for releasing the actuating means therefrom 70 when the post is struck by the ball, substantially as described. 75
17. In apparatus for playing base-ball, an umpiring device comprising a plurality of posts with spaces therebetween, a pivot for each post, means for holding the posts in position and for preventing the posts from turning on their pivots in one direction and a spring connected with one of the posts to return it to position when moved 80 therefrom, substantially as described. 85
18. In apparatus for playing base-ball, the combination of a thread, a ball suspended by the thread and an umpiring device comprising a plurality of posts with spaces 90 therebetween, a pivot for each post, means for holding the posts in position and for preventing the posts from turning on their pivots in one direction and a spring connected with one of the posts to return it to position when moved therefrom, substantially as described. 95
19. In apparatus for playing base-ball, the combination of a movable ball, a movable bat, means for actuating the bat, three posts with spaces therebetween, and means connecting one of said posts with said actuating means and adapted to set said actuating means in motion when said post is struck by said ball, substantially as de- 100 scribed. 110

In witness whereof I have signed this specification in the presence of two witnesses, this 13th day of March, 1912.

HERMAN SCHUM.
